UNITED STATES PATENT OFFICE.

MARIE GASSET, OF OGDEN, UTAH.

MAGAZINE POWDER PUFF.

1,409,370.

Specification of Letters Patent. Patented Mar. 14, 1922.

Application filed July 23, 1921. Serial No. 487,025.

To all whom it may concern:

Be it known that I, MARIE GASSET, a citizen of the United States, residing at Odgen, in the county of Weber and State of Utah, have invented certain new and useful Improvements in Magazine Powder Puffs; and I do hereby declare the following to be a full, clear, and exact description of the same, reference being had to the accompanying drawings, forming part of this specification.

This invention relates to powder puffs and particularly to that type commonly known as magazine powder puffs for the reason that it is provided in its interior with a chamber or reservoir adapted to contain a considerable quantity of powder in order that the puff alone need be carried by the user.

While this type of puff has heretofore been produced in various forms they have all been so designed that their cost of manufacture has rendered their salability quite difficult and an object of the present invention is to provide a magazine powder puff that, while efficient and durable, can be manufactured at a comparatively low cost, due to its simplicity and inexpensiveness of materials.

Practically all puffs of this character, that is the magazine type, have a bellows action for discharging the powder through the face of the puff and a further object is to provide means for functioning as a bellows that will not rust or that can be removed and cleaned, or, should it lose its resiliency, it can be readily replaced.

In the accompanying drawings—

Figure 1 is a top plan view of the puff; Fig. 2 is a sectional view on the line 2—2, of Fig. 1, showing the interior of the puff with the present improvements incorporated therein;

Fig. 3 and Fig. 4 are detail views of the bellows functioning means for expelling the powder from within the puff through the face of the latter.

The covering 10 is made of the usual material, that is, a textile fabric having a pile, and the puff is formed in the usual shape. The material has minute passages or perforations therein in order that the powder may pass through the face 11 thereof. According to the present invention, to reduce the cost of manufacture, no special container for the powder in the interior of the puff is employed, the chamber formed by

the puff itself being utilized as the powder reservoir.

The top of the puff is provided with a filling opening 12 adapted to be closed by a cover 13 and to assist in holding the puff in shape an annular rigid metal ring 14 of less diameter than the puff, is secured in the interior and at the top of the puff. There is an opening 12^a in said ring through which the powder is introduced into the puff and a flange 14^a is formed around said opening 12^a, the material forming the puff 10 being drawn and secured around said flange 14^a by a thread 15 or in any other desired manner. Cover 12 is provided with a depending circular flange 14^b adapted to telescope within flange 14^a on ring 14, the frictional engagement between the two flanges being sufficient to hold cover 12 in place on the puff.

In the preferred form of construction the bellows action for expelling the powder through the face 11 of the puff is obtained by a rubber insert positioned in the interior of the puff. Said rubber insert consists of an annular piece of rubber 16 conforming, in shape, to that of ring 14 and lies practically flat against said ring at the top of the puff. Connected to the outer edge of said rubber ring 16 are a plurality of strips or fingers 17, also preferably made of rubber but of any desired shape, which extend down and engage the interior wall of the face 11 of the puff. The ring 14 against which the rubber ring 16 seats is substantially rigid and due to the resiliency of the strips or fingers 17 the puff is normally maintained expanded, but when the face of the puff is pressed against one's skin the fingers 17 and the puff are compressed. This compressing of the puff will expel or discharge a sufficient quantity of powder through the minute orifices in the face 11.

Usually when there is any appreciable quantity of powder in the puff only the lower portion of the puff need be compressed but to permit of greater compression the rubber ring 16 is made larger than and extends beyond the edge of the annular metal ring 14 so that the upper portion may also be compressed until the puff is practically flat. With a construction such as this there will always be a discharge of powder unless there is very little, or no, powder at all in the puff.

There is, of course, an opening in the rubber ring 16 through which powder may be

poured into the puff and to hold said ring in shape a piece of material, such as gauze, is secured therein, the meshes in the gauze being of sufficient size as to not hinder the filling of the puff.

While the resilient fingers or strips 17 may be given any desired shape they are preferably made of relatively heavy rubber and crossed one upon the other, this latter feature imparting a sufficient stiffness to the puff to hold in shape while permitting the puff to be easily compressed or flattened. The fingers, together with the rubber ring 16, being of rubber, any moisture that may 15 penetrate the puff will not cause them to rust and lose their resiliency. Furthermore, they can, if desired, be removed and washed without danger of them rusting after being replaced and the particles of rust mixing 20 with the powder in the puff.

The cost of production of puffs made in accordance with the present invention is comparatively low for the reason that no supplemental container is necessary for holding the powder, the material forming 25 the puff being utilized as the reservoir or container.

What is claimed is:

1. In a magazine powder puff, the combination of a puff of pliant material through

which the powder therein is adapted to be expelled, and resilient means secured within the puff comprising a body portion and a plurality of relatively narrow fingers or strips connected to the body portion and positioned against the interior of the face of the puff for yieldingly maintaining the puff distended.

2. In a magazine powder puff, the combination of a puff of perforate, pliant material, an annular flat ring member within the puff having a filling opening thereon and having the puff material attached thereto, a cover for the filling opening, and resilient means for yieldingly holding the face of the puff distended, said means comprising a flat annular ring portion and a plurality of strips connected to the ring portion and engaging the face of the puff.

3. In a magazine powder puff, the combination of a puff of perforate, pliant material, and resilient means for holding the face of the puff yieldingly distended, said resilient means comprising a flat annular ring like body portion and a plurality of strips connected to the ring like portion and engaging the face of the puff, said strips being crossed over each other intermediate their ends.

MARIE GASSET.
